UNITED STATES PATENT OFFICE.

WILLARD H. KEMPTON, OF MANSFIELD, OHIO, ASSIGNOR TO THE OHIO BRASS COMPANY, OF MANSFIELD, OHIO, A CORPORATION OF NEW JERSEY.

WIRE-CLAMP.

1,147,870.

Specification of Letters Patent. Patented July 27, 1915.

Application filed August 10, 1911. Serial No. 643,449.

To all whom it may concern:

Be it known that I, WILLARD H. KEMPTON, a citizen of the United States, residing at Mansfield, in the county of Richland and 5 State of Ohio, have invented certain new and useful Improvements in Wire-Clamps, of which the following is a specification.

This invention relates to devices for clamping wires and the like and suspending 10 them from a hanger, and in the present exemplification of the invention is more particularly described as a clamp for trolley wires.

The principal object of the invention is 15 to provide a device of the class described, which is simple, durable and cheap in construction, and effective and efficient in operation.

For the attainment of these ends, and the 20 accomplishment of other new and useful objects, as will appear, the invention consists in the features of novelty in the construction, combination and arrangement of the several parts, generally shown in the 25 drawing and described in the specification, but more particularly pointed out in the appended claims.

In the accompanying drawing Figure 1 is a 30 side elevation of a clamp constructed in accordance with the principles of this invention; Fig. 2 is a cross sectional view of a clamp in position upon a hanger; Fig. 3 is a sectional view in elevation; Fig. 4 is an 35 end view of the clamp showing the jaws in distended position; Fig. 5 is a detail side view of the suspension member.

In clamps of the class described, such as 40 are used for trolley wires, and the like, it is necessary that the clamping jaws should be disposed at the proper angle and a clamp 45 is desired which is simple and cheap, and at the same time possesses the requisite strength and rigidity to support the wires. Furthermore, it is desired that the clamp 50 should be readily adjustable in position and can be permanently secured to the wires. This clamp is adapted to fulfil these requirements and present a structure which is 55 effective and efficient in operation.

50 Referring now more particularly to the drawings, a suspension member is formed with an internally threaded opening 11 and an outside notch or notches 12, which are disposed in the outer face of the member. 55 At the other end of the suspension member is an inverted wedge shaped portion 13 with

an extending tip 14, both being joined to the threaded portion by the neck 15. A pair of jaw members 16 and 17 are formed with inter engaging portions adjacent the ends 60 thereof, one of the members being formed with openings 18 through which lug 19 from the other member extend, the said openings and projections forming a pivotal bearing for the jaw members. One edge of 65 each of the said jaws is formed with the clamping portion 20, which are adapted to be placed in proximity to each other, and the other edge of each of the jaw members is formed with inwardly extending lips 21, 70 which bear upon the inclined faces of the wedge shaped portion 13. The upper edges of the jaw members 16 and 17 are also inclined inwardly, as shown by Fig. 4, so that the outermost edge of the members is the 75 highest. Intermediate of the ends of the jaw members and extending inwardly thereof are the ribs 22, which are adapted to engage the projecting tip 14 of the suspension member and to prevent the jaw members 80 from tilting upon the suspension member. The jaw members are rotatable upon each other to an extent limited by the ribs 22 bearing on the tongue 14 in one direction, and by lips 21 bearing on neck 15 in the 85 other direction.

A sleeve 24 formed with a projecting lug or lugs 25 is adapted to fit around the suspension member, the lugs 25 extending into the slots 12, and permitting a longitudinal 90 movement of the sleeve with respect to the suspension member and preventing the rotation of it with respect to the suspension member. This sleeve 24 is threaded, preferably on the outside, and adapted to receive an operating nut 26. The nut 26 is adapted to be moved upon the sleeve 24, to adjust the position of the sleeve, the under surface of the nut 26 bearing upon the edges of the jaw members, the lips 21 of which 100 bear upon the faces of the inverted wedge portion 13. To position the clamp the suspension member is threaded on the stud of a hanger member 27 until it nearly bears against the hanger body and the clamping 105 edges of the jaw members are in the desired alinement, the trolley wire as A is passed between the clamping edges of the jaw members and the operating nut is moved about the sleeve 24 until the sleeve bears against 110 the hanger or against the ends of the slots in the suspension member, and the face of

the operating nut bears upon the upper edges of the clamping jaws. By continuing the rotation of the operating nut 26 the clamping jaws may be applied with any desired pressure, and it will be seen that the 5 jaws are applied by the action of the inverted wedge which bears upon the lips 21 of the said members. This action is in effect the withdrawal of the inverted wedge shaped portion relatively with respect to the 10 jaws. Since the jaws are pivotally mounted at their center the separating action of the wedge on one side of the pivotal mounting effects the clamping action on the other side of the pivotal mounting.

15 It is evident that the clamp may be attached to a trolley wire just tight enough to hold the wire in position until it has been stretched. The clamp may then by one operation be permanently tightened upon the 20 trolley wire and the hanger, thus eliminating loose joints between the clamp and the hanger. It is furthermore evident that the 25 clamping jaws may be disposed about the hanger at any angle thereto, and the clamp secured in the adjusted position.

30 While I have thus described the preferred construction, combination and arrangement of the several parts which constitute my invention, it is evident that others skilled in the arts to which this relates may make 35 various changes without departing from the spirit and scope of the invention.

What I claim is:—

35 1. In a trolley clamp, the combination with a member threaded to receive a hanger stud and formed with an upwardly converging wedge portion, of interengaging freely pivoted jaw members with inclined edges 40 disposed over and adapted to coat with the said wedge portion and other edges movable into clamping position when the wedge is moved upwardly, and means to draw the said wedge portion upwardly with respect 45 to the jaws to move the clamping edges together.

50 2. In a trolley clamp, the combination with a member threaded at one end for attachment to a hanger and with a wedge shaped portion at the other end, of pivotally freely movable interengaging jaw members the edges of which are formed with lips which engage the wedge surfaces and the other edges are formed with clamping 55 portions, and means to press against the edges of the jaw members adjacent the wedge surfaces whereby the jaws and the wedge shaped portion are relatively moved, to apply the clamping edges.

60 3. In a trolley clamp, the combination with a suspension member internally threaded at one end and having a wedge-shaped portion at the other end, of pivotally interengaging jaw members having edges which 65 bear upon the wedge portion, a sleeve which

fits over the suspension member, and an operating nut threaded upon the sleeve and operative to press the jaw members along the wedge surfaces whereby the clamping edges of the jaw members are applied. 70

4. In a trolley clamp, the combination with a suspension member internally threaded for a hanger bolt at one end and formed with a wedge-shaped portion with a projecting end tip at the other end, of pivotally 75 interengaging jaw members having edges which are adapted to ride on the wedge-shaped portion, the tip extending between the jaw members to position them and prevent the tilting thereof with respect to the 80 wedge portion, and means to apply the clamping jaws.

5. In a trolley clamp, the combination with a suspension member internally threaded for a hanger bolt at one end and formed 85 with a wedge-shaped portion with a projecting end tip at the other end, of pivotally interengaging members with edges disposed to bear on the wedge-shaped portion and formed with ribs adjacent the said tip, and 90 adjustable means to vary the pressure and position of the jaw members on the wedge-shaped portion, the said tip being adapted to engage the ribs to prevent the jaw members from tilting. 95

6. In a trolley clamp, the combination with a suspension member internally threaded at one end to receive a hanger stud and formed with a wedge-shaped portion with a projecting tip at the other end and a longitudinal 100 slot in the outer face of the threaded portion, of jaw members pivotally interengaging and with edges riding on the wedge faces and held from tilting by the said tip, a sleeve formed with a projection to enter 105 the said slot, externally threaded and slideable along the suspension member, and an operating nut threaded upon the sleeve operative to bear the edges of the jaw members upon the wedge-shaped portion and to 110 move the latter relatively upward from the jaw members whereby the clamping edges of the jaws are adjusted and applied.

7. In a trolley clamp, the combination with a suspension member internally threaded at one end to receive a hanger stud and formed with an upwardly converging wedge-shaped portion, with a projecting tip at the other end and a longitudinal slot in the outer face of the threaded portion, of 115 jaw members pivotally interengaged adjacent their center, the edges being formed with inwardly extending lips which are adapted to slide on the wedge shaped portion, a sleeve having a projection engaged 120 by and slideable in said slot to hold the sleeve against rotation with respect to the suspension member, an operating nut threaded upon the sleeve and adapted to bear against the upper edges of the jaw 125 members. 130

- members, the said nut being operative to move the wedge shaped portion of the suspension member upwardly from and with respect to the jaw members, whereby the 5 lower edges of the members are applied, the said upper edges of the jaw members being inclined so that the nut contacts with the edges of the members in distended position whereby greater pressure is brought to bear 10 in applying the jaws by means of the nut.
8. In a trolley clamp, the combination with a suspension member internally threaded at one end to receive a hanger stud and formed with a wedge-shaped portion with 15 a projecting tip at the other end and a longitudinal slot in the outer face of the threaded portion, of jaw members pivotally interengaged adjacent their center, the edges being formed with inwardly extending lips 20 which are adapted to slide on the wedge shaped portion, a sleeve having a projection engaged by and slidably in said slot to hold the sleeve against rotation with respect to the suspension member, a nut threaded upon 25 the sleeve, bearing upon the edges of the jaw members and adapted, when operatively moved, to press the sleeve until it contacts with the hanger and to close the clamping jaws by drawing the wedge-shaped portion 30 of the clamping member upward relatively to the jaws, the jaws being thereby adjustable at any angle about the hanger and the jaws being applied by a single operation of the said nut.
- 35 9. The combination with a hanger for wires, of a supporting clamp embodying pivoted clamping jaws movable apart on one side of the pivot to clamp a wire between them on the other side, a sleeve mov- 40 ably mounted on said clamp, a nut threaded with the sleeve and adapted when operatively rotated to extend the outer ends of the nut and sleeve to press said sleeve against the hanger and to press the nut 45 downwardly upon the top of the jaws spreading them apart on the adjacent side of the pivotal mounting.
10. The combination with a hanger for wires, of a supporting clamp embodying 50 pivoted clamping jaws adapted to be closed to grip a wire, a sleeve movably mounted on said clamp, a nut threaded with the sleeve and adapted when operatively moved to extend the outer ends of the nut and sleeve 55 and to tightly position the clamp with respect to the hanger and the jaws, and to close the clamping jaws.
11. The combination with a hanger member, of a supporting member adapted to be 60 removably mounted upon said hanger member, another member interlocked for rotation with said supporting member, clamping jaws carried by said supporting mem- ber, and common means for jamming said interlocked member against said hanger 65 member and for actuating the clamping jaws.
12. The combination with a hanger member, of a supporting member removably attached thereto, a sleeve member rotatably 70 interlocked for rotation with said supporting member adapted to be set tightly against the hanger member to bind the supporting member against rotation, wire clamping jaws suspended from said sup- 75 porting member and adapted to be actuated to clamp the trolley wire, and means common to both said sleeve member and said clamping jaws for actuating them.
13. The combination with a hanger mem- 80 ber having a threaded stud, of a socket member adapted to be screwed on to said stud, a sleeve member interlocked for rotation with said socket member and adapted to be jammed against the hanger member to 85 bind the socket member against rotation, means carried by the socket member for clamping a trolley wire, and a common de- 90 vice for actuating said sleeve member and said wire clamping means.
14. The combination of a hanger member having a depending stud, a socket member adapted to be screwed on to said stud, a threaded sleeve rotatably interlocked with said socket member but movable longitudinally thereof and adapted to be jammed against said hanger member to bind said socket member against rotation, wire clamp- 95 ing means on said socket member, and a threaded collar on said sleeve adapted, when 100 rotated, to actuate said sleeve and said wire clamping means.
15. The combination of a pair of hinged wire clamping members, a threaded socket member having a spreader positioned be- 105 tween the said clamping members, a hanger member having a threaded stud adapted to be screwed into said socket member, a sleeve longitudinally movable relatively to said socket member but interlocked therewith 110 against relative rotation and adapted to be moved against said hanger member to bind the socket member against rotation, and a collar threaded on said sleeve for actuating said sleeve and for forcing the clamping 115 members against said spreader to cause them to move apart.
- In testimony whereof I have signed my name to this specification, in the presence of two subscribing witnesses, on this 3rd day 120 of August A. D. 1911.
